Rodney G. Richardson

R. G. Richardson Atty:

UNITED STATES PATENT OFFICE

RODNEY G. RICHARDSON, OF CHICAGO, ILLINOIS

VIBRATING DEVICE

Original application filed January 10, 1924, Serial No. 685,344. Divided and this application filed July 1, 1929. Serial No. 375,011.

My invention relates in general to vibrating devices, and is especially applicable to vibrating screens, although its use is not so limited; and the object is to provide an arrangement and means for utilizing the gyroscopic couples generated by vibrating the axis of rotation of a heavy fly wheel or gyroscope, thereby producing a powerful and efficient vibrating device. This application is a division of application serial No. 685,344, filed January 10, 1924, now patent No. 1,726,192, in which the invention referred to in the foregoing is described and claimed. In this divisional application, a special adaptation of my invention is described, according to which a gyroscopic device is employed in connection with apparatus having a primary movement in order to impart to such apparatus a translated secondary movement.

One embodiment of my invention, in which the same is applied to a vibrating screen of the well-known type used for screening or grading sand, gravel, ore, and like material, is shown in the accompanying drawing, wherein:

Fig. 1 shows a top view of a screen equipped with the invention;

Fig. 2 shows a side view of the same screen;

Referring to Figs. 1 and 2, the screen itself may be of any approved type. As shown herein it comprises a rectangular wooden frame about 8 ft. over all in length, and 2 ft. in width, with an inner frame of square strips on which a sheet metal or wire mesh screen is stretched and held by staples, cleats, or any suitable means. The method of construction is sufficiently indicated in the drawing, and since it is well understood by persons familiar with screens, no further consideration will be necessary on this phase of the matter.

The means for supporting the screen will now be explained. The sides 2 and 3 of the frame are attached at opposite ends to the cross pieces 4 and 5, which support the weight of the frame. The cross pieces 4 and 5 are in turn supported by means of springs on cross pieces 6 and 7, respectively.

The latter may form part of some other machine, or may be supported in any preferred manner, depending on the circumstances. As shown two heavy sill pieces of 2 x 6 inch timber are set on edge and the lower cross piece 7 fits in a mortise about a foot from the left end. At the right the cross piece 6 is supported by two uprights, one of which is indicated by reference character 10, at such a height that the screen will be inclined at an angle of about 30° from the horizontal.

The springs which support the cross pieces 4 and 5 are four in number and are indicated by reference characters 11 to 14, inclusive. These springs evidently constitute a loose or flexible support for the frame of the screen, on which it is free to vibrate.

The primary mechanism for causing the screen to vibrate may now be considered. This comprises a driven shaft 50 supported on bearings 51 and 52, which in turn are supported on frame members 20 and 21; and a pair of connecting rods or pitmen 53 and 54 suitably connected to the shaft 50 and the sides of the screen frame. It will be evident that rotation of the shaft 50 will cause a reciprocating movement of the screen.

The secondary actuating apparatus may now be considered. This comprises a heavy fly wheel or gyroscope 40 and shaft 41, supported on self-aligning ball bearings 42 and 43. Bearing 42 is rigidly secured to the frame of the screen by means of a member 44 and the two cross pieces 45 and 46. The other bearing, bearing 43, is secured to the upper end of a rigid member 70, attached to members 9 and 20 as shown.

The gyroscope shaft is rotated by a pulley wheel 54 and belt 55, with a small motor (not shown). The shaft 50 may also be belt driven, but preferably at a lower speed.

The operation is as follows: Rotation of the shaft 50, as heretofore mentioned, imparts a reciprocating movement to the screen. The direction of the forces applied to the screen are such as to vibrate it in a substantially horizontal plane. This movement of the screen may be termed the primary movement. The secondary movement of the

screen is produced by the gyroscope 40 as a result of the precession of its axis or shaft caused by the primary movement. In brief, vibrations of the screen in a horizontal plane will cause the screen bearing of the gyroscope to vibrate, and the gyroscope, reacting against the fixed bearing 43, will set up secondary vibrations in the screen in a vertical plane. The path actually followed by the screen in its movement, therefore, will be the resultant path which is determined by the horizontal and vertical components.

Numerous modifications are possible, and I do not therefore wish to be limited to the constructions described herein, but desire to include and have protected by Letters Patent all forms of my invention which come fairly within the scope of the appended claims.

20. What is claimed is:

1. In combination, a frame, means for vibrating said frame primarily, and means for vibrating said frame secondarily, said second means comprising a gyroscope, a bearing 25 for the shaft of said gyroscope supported independent of said frame, and a second bearing for said shaft supported on said frame.
2. The combination, with a movable apparatus, of means responsive to movement of 30 said apparatus and means for moving the same in one direction for moving the same in another direction, said means comprising a gyroscope the shaft of which has one end connected to said apparatus, together with a 35 fixed outside support for the other end of the shaft.
3. The combination, with an apparatus having a reciprocating movement, of means 40 for giving said apparatus an auxiliary reciprocating movement in another plane, said means comprising a gyroscope, a bearing for one end of the gyroscope shaft connected to said apparatus so as to move therewith, and a bearing for the other end of said shaft 45 connected to a rigid outside support, so that by reacting against said support the said gyroscope produces the auxiliary reciprocating movement as set forth.
4. In combination, a movable body means 50 for moving said body, a gyroscope, a connection between said body and gyroscope whereby movement of the body in one plane will cause precession of the gyroscope, a second body, and a connection between said second body and said gyroscope to enable the gyroscope to cause movement of the said first body in a different plane by reaction against 55 said second body.
60. 5. In combination, a body movable in two planes, means for moving said body in one plane, a gyroscope arranged to precess responsive to movement of said body in said one plane, and an outside support for said 65 gyroscope against which the same reacts dur-

ing precession to move said body in a different plane.

6. In combination, a movable body, means for moving said body, a gyroscope, means connecting said body and said gyroscope whereby movement of the body will cause precession of the gyroscope, and a second body against which said gyroscope reacts during precession to apply a force to said first body through said connecting means and change the direction of movement of said first body.

7. In combination, a movable body, means for applying a force to said body tending to move it in a given direction, a gyroscope supported on said body and arranged to precess responsive to said movement, a second body, and means whereby said gyroscope reacts against said second body during precession and applies a force to said first body which changes the direction of movement thereof.

In witness whereof, I hereunto subscribe my name this 28th day of June, A. D. 1929.

RODNEY G. RICHARDSON.
